UNITED STATES PATENT OFFICE.

GEORGE W. PELTON, OF MUSCATINE, IOWA.

WEATHER-BOARDING TOOL.

SPECIFICATION forming part of Letters Patent No. 365,857, dated July 5, 1887.

Application filed March 24, 1887. Serial No. 232,257. (No model.)

To all whom it may concern:

Be it known that I, GEORGE W. PELTON, a citizen of the United States, residing at Muscatine, in the county of Muscatine and State 5 of Iowa, have invented certain new and useful Improvements in Weather-Boarding Tools; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 The invention will first be described in connection with the drawings, and then pointed out in the claims.

Figure 1 of the drawings is a perspective view showing my invention applied; Fig. 2, a 20 side elevation of the tool with the stop raised and the spring compressed.

In the drawings, A represents the supporting-frame, provided with the shoulder *a*, which abuts against the lower edge of a weather-board, 25 B, under which passes the blade C. The latter is made fast on the flat bottom of the frame A, which has on its rear end a finger-loop, D.

On the frame A, and just above the shoulder, is made fast one end of a flat metallic spring, 30 E, whose other end extends up under a lever, F, fulcrumed at *f* on the front end of the frame A.

f' is a subjacent projection on the lever, the same being provided with two or more holes, 35 *f*², through either of which may pass the fulcrum-pin G, that connects the two frame-ears *a*. On the upper and inner end of the lever F is made fast the pointed stop H.

The tool thus forms a weather-board self-

supporting rest and gage adapted to support 40 a weight of about thirty-five pounds and to be used as follows: Three fingers of the left hand are placed in the loop D and the thumb over the free end of the lever F. The spring is then compressed, the stop raised, and the blade 45 pushed under the lower edge of the weather-board B. The thumb is now removed from the lever and the pointed stop allowed to come down upon the upper part of weather-board B. A tap on the front end of lever will then 50 make the gage fast in its place, when the lower edge of another weather-board may be placed against the stop.

Having thus described all that is necessary to a full understanding of my invention, what 55 I claim as new, and desire to protect by Letters Patent, is—

1. In a weather-boarding tool, the frame A, having the shoulder *a* to bear against the butt-end of a shingle, a blade, C, to pass under 60 it, a finger-loop, D, on the rear end, and a superposed plate-spring, E, in combination with a lever, F, fulcrumed on the front end of said frame and carrying under its front end a pointed stop, H, substantially as shown and 65 described.

2. In a weather-boarding tool, the combination, with a lever having a pointed stop at its front end and supported at the rear by a spring, of a finger-loop arranged under the 70 rear end of the lever, as and for the purpose specified.

In testimony whereof I affix my signature in presence of two witnesses.

GEORGE W. PELTON.

Witnesses:

WILLIAM FREELAND,
FRANK E. KILLMER.
